UNITED STATES PATENT OFFICE.

LOUIS N. D. WILLIAMS, OF OGONTZ, PENNSYLVANIA.

STITCH TRANSFERRING AND UNITING DEVICE

Specification of Letters Patent. Patented June 20, 1916.

1,188,125.

Application filed August 6, 1915. Serial No. 43,958.

To all whom it may concern:

Be it known that I, Louis N. D. Williams, a citizen of the United States, residing in Ogontz, Pennsylvania, have invented 5 certain Improvements in Stitch Transferring and Uniting Devices, of which the following is a specification.

My invention relates to a method of uniting knitted webs which consists in first 10 gaging two sets of stitch receiving quills or points (hereinafter, for convenience, termed "points") with the stitches to be united, then adjusting said sets of points, with the 15 stitches upon them, into close relation to one another, and then uniting, by means of a 20 separately produced chain of stitches, successive stitches or successive pairs of stitches of the knitted web, while said stitches are still upon the original transfer points, and without transferring the stitches of one set 25 of points, onto the other set of points.

My invention further relates to the disengagement of the points and stitches after the webs have been united.

These objects I attain in the manner hereinafter set forth, reference being had to the accompanying drawing, in which—

Figure 1 is a sectional view of sufficient of 30 a circular knitting machine to illustrate the application thereto of a device in accordance with my invention for engaging the stitches of the knitted web carried by the needles of said machine, said device being in position to receive said stitches; Fig. 2 is a sectional 35 view, on a larger scale, showing the two sets of stitch engaging points adjusted back to back so as to bring the stitches into position to be united; Fig. 3 is a view similar to Fig. 2, but showing the stitch engaging points 40 freed from the united stitches; Fig. 4 is an enlarged diagram showing in full lines the two sets of terminal stitches and the chain of stitches whereby the successive stitches of the webs are united, in pairs and showing in 45 dotted lines the positions assumed by the stitch carrying points during such operation; Fig. 5 is a similar view showing in dotted lines the positions assumed by the 50 stitch engaging points previous to disengaging them from the stitches; Fig. 6 is a view similar to Fig. 1, but showing a different form of stitch engaging device from that there represented; Fig. 7 is a sectional view

of said device with the stitch engaging points in position to permit of the uniting 55 of the successive stitches of the knitted webs; Figs. 8 and 9 are sectional views illustrating successive steps in the operation of disengaging said stitch engaging points from the united stitches; Fig. 10 is a view similar to 60 Fig. 1, but illustrating still another form of stitch engaging device; Fig. 11 is a view of said device with the stitch-engaging points adjusted to position for the uniting of the successive stitches of the knitted webs, and 65 Fig. 12 is an enlarged diagram, illustrating the stitches whereby said successive stitches of the knitted webs are united.

In the drawing I have only shown a single 70 pair of diametrically opposite wales, and the points which engage them, as the showing of the other wales and points would only cause confusion.

The stitch engaging device may, in the 75 case of a circular web, consist of two semi-circular segments 1 and 2, each provided with a segmental series of stitch engaging points 1^a or 2^a which, when the segments 1 and 2 are in the position shown in Fig. 1, will engage the stitches upon the needles of 80 the circular knitting machine or the stitches of a previous course. Each point 1^a of the segment 1 corresponds with a point 2^a of the segment 2, and the stems 1^b and 2^b of the 85 stitch receiving points shown in Figs. 1, 2 and 3 project beyond the segments 1 and 2 and said projecting portions of the stems are so bent that when the segments are folded, as shown in Fig. 2, the corresponding points 1^a and 2^a will abut against each 90 other back to back and will prevent the segments 1 and 2 from being brought closely together. When the points are in this position the stitches *x*, *x*, of the webs are close 95 enough to be united in pairs by a chain of stitches *y*, as shown in Fig. 4. After this has been done, one of the segments is shogged slightly in respect to the other so as to alternate the points 1^a and 2^a, as shown in Fig. 5, and thus permit the segments 1 and 2 to approach each other back to back, as shown in Fig. 3, and thereby disengage 100 the points from the stitches *x*, *x*, after which the entire point structure can be readily removed from between the two webs.

When the chain of stitches *y* which con-

nects the stitches α , α , of the webs is relatively slack, a stitch engaging device such as shown in Figs. 6 to 9 can be employed, the segments 1 and 2 of such device having stitch engaging points 1^a and 2^a with straight shanks which permit of the folding of the segments back to back, as shown in Fig. 7, without withdrawing the points 1^a and 2^a from the stitches carried thereby, but the 10 uniting chain of stitches γ will permit the entire point carrying structure to be moved laterally so as to disengage one set of points, say the points 1^a, from the stitches α of its web, as shown in Fig. 8, after which the segment 15 1 and its points 1^a can be removed from between the webs, as shown in Fig. 9, in order to permit sidewise movement of the segment 2 and its points to an extent sufficient to free the latter from engagement 20 with the stitches α of its web and subsequent removal from between the webs.

It may be advisable in some cases to provide the segments shown in Figs. 1, 2 and 3 with an elastic band 5 seated in grooves 25 in the segments and tending to draw said segments toward each other either when adjusted edge to edge, as shown in Fig. 1, or when adjusted back to back, as shown in Figs. 2 and 3, but this is not essential, nor 30 is it essential that the point carriers shall be in the form of segments, since, when employed in connection with straight knitting machines instead of circular knitting machines, said point carriers may consist of 35 straight flat bars.

The stitches of the connecting chain γ shown in Figs. 7, 8 and 9 may be slack enough to permit disengagement of the points 1^a and 2^a from the stitches α without 40 affecting either the secure retention of said stitches or impairing the appearance of the connecting seam.

In that embodiment of my invention shown in Figs. 10, 11 and 12, the points 1^a and 2^a, after receiving the stitches from the needles of the knitting machine, are brought together and alternated, as shown in Figs. 11 and 12, so that the points may overlap, and thus bring the terminal stitches α of the 50 two webs close enough to be united by a chain of stitches γ which engages with successive individual stitches α of each web, as shown in Fig. 12, instead of uniting the stitches in pairs, as shown in Fig. 4.

55 I claim:—

1. The mode herein described of uniting the terminal stitches of knitted webs, said mode consisting in engaging one set of said 60 stitches with one set of stitch-engaging points and the other set of stitches with another set of such points, then, without removing the stitches from their engaging points, bringing said stitches into prox-

imity to one another, then uniting them by means of an independently produced chain 65 of stitches, and then disengaging each set of points from the stitches engaged thereby.

2. The mode herein described of uniting the terminal stitches of knitted webs, said mode consisting in engaging one set of said 70 stitches with one set of stitch-engaging points and the other set of said stitches with another set of such points, then bringing the two sets of stitches into proximity to one another, then, without removing the stitches 75 from their engaging points, uniting said webs by an independently produced chain of stitches, each stitch of said chain engaging a pair of stitches, comprising a stitch of each web, and then disengaging each set of 80 points from the stitches engaged thereby.

3. The mode herein described of uniting the terminal stitches of knitted webs, said mode consisting in engaging one set of said 85 stitches with one set of stitch-engaging points and the other set of stitches with another set of such points, then bringing the two sets of stitches into proximity to one another, then, without removing the stitches 90 from their engaging points, uniting said webs by an independently produced chain of stitches, each stitch of said chain engaging a pair of stitches comprising a stitch of each web, then shogging the stitches of one 95 web in respect to those of the other web so as to cause them to alternate, and then disengaging each set of points from the stitches engaged thereby.

4. In apparatus for effecting the uniting of the terminal stitches of knitted webs, the 100 within described means for engaging said terminal stitches and adjusting them into position to be united, said means comprising a pair of bars adjustable edge to edge or back to back, and each carrying a set of 105 stitch engaging points projecting therefrom in a plane at a right angle or thereabout to the plane of the bar.

5. In apparatus for effecting the uniting of the terminal stitches of knitted webs, the 110 within described means for engaging said terminal stitches and adjusting them into position to be united, said means comprising a pair of bars adjustable edge to edge or back to back and each carrying a set of 115 stitch engaging points projecting therefrom in a plane at a right angle or thereabout to the plane of the bar, said points having bent stems which, when the points are adjusted back to back, prevent like contact of the 120 carrier bars.

6. In apparatus for effecting the uniting of the terminal stitches of knitted webs, the 125 within described means for engaging said terminal stitches and adjusting them into position to be united, said means comprising

a pair of bars adjustable edge to edge or back to back and each carrying a set of stitch engaging points projecting therefrom in a plane at a right angle or thereabout to the plane of the bar, said points having bent stems which, when the points are adjusted back to back, prevent like contact of the carrier bars, and said carrier bars being susceptible of being shogged so as to move the

points from back to back position into alternating position.

In testimony whereof, I have signed my name to this specification, in the presence of two subscribing witnesses.

LOUIS N. D. WILLIAMS.
